UNITED STATES PATENT OFFICE.

GEORGE L. JENKINS, OF PHILADELPHIA, PENNSYLVANIA, ASSIGNOR TO
THE AUSTIN, NICHOLS & COMPANY, OF NEW YORK, N. Y.

DESIGN FOR A BOTTLE.

SPECIFICATION forming part of Design No. 25,942, dated August 18, 1896.

Application filed June 19, 1896. Serial No. 596,218. Term of patent 14 years.

To all whom it may concern:

Be it known that I, GEORGE L. JENKINS, a citizen of the United States, residing at Philadelphia and State of Pennsylvania, have invented and produced a new and original Design for Bottles, of which the following is a specification.

In the accompanying drawings I have illustrated the design.

- 10 Figure 1 is a bottom plan showing the oval form of the complete bottle. Figs. 2 and 3 are sectional views a quarter-turn from each other. Fig. 4 is a side view, and Fig. 5 a side view a quarter-turn from Fig. 4.
- 15 The leading feature of my design consists in a bottle having a contracted neck portion terminating in a flaring lip and with a body portion flaring outwardly from said neck portion and elongated in cross-section in the direction of its sides, giving a slightly-flattened

appearance. The neck of the bottle is shown at *a* and has a flaring lip *e*, and at the base of the neck a bead *c* projects, defining the limit of the neck. From this bead the body of the bottle flares outwardly, its diameter ²⁵ enlarging beyond that of the neck, being of greater width from side to side than from front to back. The body of the bottle joins the bottom on straight lines and forms a plane base, without flaring and without a foot. ³⁰

What I claim is—

The design for a bottle herein shown and described.

In testimony whereof I affix my signature in presence of two witnesses.

GEORGE L. JENKINS.
